UNITED STATES PATENT OFFICE.

FRANK E. HEFFERNAN, OF SALT LAKE CITY, UTAH.

HAT-FASTENER.

SPECIFICATION forming part of Letters Patent No. 787,573, dated April 18, 1905.

Application filed December 13, 1904. Serial No. 236,753.

To all whom it may concern:

Be it known that I, FRANK E. HEFFERNAN, a citizen of the United States, residing at Salt Lake City, Salt Lake county, State of Utah, have invented a new and useful Device for Securing a Hat on a Lady's Head, of which the following is a specification.

My invention relates to improvements in a device to secure a lady's hat on her head. The device is attached to the hat so that the hat is firmly secured to the hair and does not disarrange the same; second, also that the hat may be removed easily when so desired. I attain these objects by the mechanism illustrated in the accompanying drawings, in which—

Figure 1 is a vertical section view of an ordinary hat shape with the device secured thereto, the pin C being pushed in and the spiral f projecting. Fig. 2 is a side view elevation of my invention with spiral f housed as when not in use. Fig. 3 is a horizontal section view on line y y, Fig. 2; Fig. 4, an end view. Fig. 5 is a vertical transverse section on line x x, Fig. 2. Fig. 6 is an inverted view showing bottom of case A with opening g for exit of spiral f; Fig. 7, an enlarged view of part of tube C, showing brackets d with perforations p therein.

In the several figures illustrating my invention similar letters of reference refer to like parts throughout.

The brackets d when fastened to the hat secure the device to the hat and retain it in position, so that the direction taken by spiral f is into or out of the hair and by being attached to the tube B permits the horizontal movements desired for the threaded pin C and as guided by tube B, the tube B, with the brackets d, forming a support for casing A. The casing A has the top closed, so that the threaded pinion can only be raised to said top. The bottom of the casing is provided with a slotted hole g, which allows the spiral f to pass out and keep the hair from becoming entangled in the spiral f and being drawn up into casing A when spiral f is raised. The upper part of casing A (shown as a') is internally threaded, so that threaded grooves engage the

threads on the threaded pinion h, retaining it 50 in position and permitting only a vertical and rotating movement as imparted by the threads on threaded pin C engaging the threads on pinion h as the pin C is moved in or out of tube B. To the bottom of the threaded pinion h is attached spiral f.

The device is secured to the hat within the crown by sewing through the perforations p in the brackets d, (shown in Fig. 7,) the threaded pin C being drawn out, as shown in Fig. 60 3, and the spiral f within its case A, as shown in Figs. 2, 4, and 5. When the hat is then placed on the head, the contour of which is shown by line i i, Fig. 1, the threaded pin C is pushed into the tube B, and the threads on 65 pin C engaging the threads on pinion h turn the said pinion h, to the bottom of which is securely attached spiral f, so that the threaded pinion h and spiral f is lowered and by the lowering and turn given spiral f is forced out 70 through the slotted hole g in the bottom of the case A and is screwed into the hair, as shown in Fig. 1, and thus securely fastening the hat on the head.

To remove the hat, pull the threaded pin C 75 out until the rotations imparted by the threads on said pin C, engaging the threads on pinion h, raises by the rotary and upward motion the spiral f out of the hair.

Having thus described my invention, I claim 80 and desire to secure by Letters Patent—

The combination of a hollow tube with brackets at either end of the same adapted to be attached to a hat, a threaded pin within said tube, a casing supported by said tube internally threaded at one end and closed at its other end with a small opening in the same for the passage of a spiral hair-engaging device, a threaded pinion working in the internal threaded groove of the casing and engaged by 85 the threaded pin to be operated thereby, and a spiral hair-engaging device attached at one end to the threaded pinion and having its other end protruding in the opening in the casing.

FRANK E. HEFFERNAN.
